UNITED STATES PATENT OFFICE.

LOUIS M. POTTS, OF HIGHWOOD, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed September 7, 1922. Serial No. 586,619.

To all whom it may concern:

Be it known that I, LOUIS M. POTTS, a citizen of the United States, residing at Highwood, in the county of Bergen, State of New Jersey, have invented certain new and useful Improvements in Signaling Systems, of which the following is a full, clear, concise, and exact description.

This invention relates to signaling systems and particularly to control apparatus for such systems.

In certain types of telegraph systems, it is desirable to employ a sensitive relay, which will produce and maintain a certain condition in response to a signal of one polarity and will produce and maintain a different condition in response to a signal of the opposite polarity.

An object of this invention is to provide means which may be used for the above and similar purposes.

Another object of the invention is to cause an electron discharge device in which the space current is controlled by a magnetic field, or the like, to function to maintain the output circuit of the tube in a predetermined condition until a subsequent change in the magnetic field.

In accordance with the above and other objects, the invention provides an evacuated vessel containing an anode and an electron-emitting cathode with means for generating a magnetic field to control the current flowing between such electrodes, and an additional means for producing a magnetic field sufficient to maintain the output current established by the other magnetic field generating means when the current therein is reduced substantially to zero.

Referring to the drawing,

Fig. 1 illustrates diagrammatically one embodiment of the invention.

Fig. 2 illustrates a modification of the arrangement shown in Fig. 1.

In Fig. 1 of the drawing is shown a vacuum tube consisting of an elongated glass vessel 4, containing a thermionic cathode 5 which, as in other forms of vacuum tubes, is adapted to be heated to incandescence by current supplied by a battery 6, and a cylindrical anode 7, which surrounds the cathode substantially the length thereof. Space current is supplied to the tube by a battery 8 connected between the cathode and anode.

Surrounding the vessel 4 is a magnetic coil

9 supplied with current from a battery 10 and producing a magnetic field parallel to the cathode and of sufficient strength normally to prevent the flow of electrons between the cathode and anode. A second coil 11, in series with the battery 8 and the anode, also surrounds the tube. When space current is flowing a magnetic field is produced by coil 11, which opposes and nullifies that produced by coil 9 and thus permits space current to continue flowing.

A third coil 12, surrounding the tube is connected to a line 13, or other source of signals. The coil 13 carries current in either direction, depending on the polarity of the incoming signals and thus produces a field which may aid the field produced either by the coil 9 or by the coil 11.

Included in the output circuit between the battery 8 and coil 11 is a relay 14. This relay responds to changes in output current for controlling the application of negative and positive impulses to a line conductor 15. This conductor 15 may extend either to a local recording set or to a distant station in which event the apparatus just described would serve as repeating means for repeating signals from the line conductors 13 to line conductor 15.

When an impulse is impressed on magnetic coil 12 from the line conductors 13, a magnetic field is generated in a direction such as to oppose the magnetic effect of the field produced by coil 9, whereby current is caused to flow in the output circuit and continue to flow irrespective of the fact that an impulse is no longer impressed on the coil 12. The relay 14 is energized and a negative impulse applied to line 15. Likewise, if an impulse of the reverse polarity is impressed on the coil 12, the magnetic field generated by coil 11 is strengthened and the output circuit is opened and maintained open that is, no current flows in the output circuit. For such operation, relay 14 will be caused to release and close its contacts for impressing on conductor 15 an impulse of positive polarity and such impulse will continue until a subsequent change in the character of the impulse impressed on the magnetic coil 12.

In a modification in Fig. 2, three vacuum tubes 20, 21 and 22, each comprising an elongated glass vessel, a heated cathode and a cylindrical anode, together with means

for generating a magnetic field to control the current flowing between the cathode and anode electrodes, are shown. In this figure, like parts are represented by like reference characters with the prime and double prime indices added.

Each of the vacuum tubes 20, 21, and 22 is provided with a pair of windings 26 and 27, the former being the equivalent of the 10 magnetic coil 11, described in connection with Fig. 1, while the latter functions in a manner similar to coil 9, also described in connection with Fig. 1. Magnetic coils 26, 26' and 26'' are serially connected with a 15 battery 33 and the anode 25 of tube 20. Coils 27, 27' and 27'' are connected in a local circuit with a battery 34, which supplies current to these windings of a strength sufficient to maintain the output circuits of 20 these tubes in a condition predetermined by the character of the impulse received. In addition to the windings just described, vacuum tube 20 is provided with an additional winding 28. This winding 28 has its terminals connected with a pair of line conductors 30 over which impulses are adapted to be transmitted.

Associated with the output circuit of vacuum tubes 21 and 22 is a polarized relay 31, 30 which is arranged to impress on a line conductor 32 positive and negative impulses in accordance with the operation of the tube arrangement just described.

Under normal conditions, the current in 35 windings 27 and 27' of tubes 20 and 21, respectively, is of sufficient strength to maintain the output circuits of these tubes open, while the current through winding 27'' on tube 22 is not of a strength sufficient to hold 40 the output circuit of tube 22 open. If an impulse is impressed on the conductors 30, such impulse will pass through winding 28 in a direction to oppose the effect of winding 27. The output circuit of tube 20 will be 45 closed thereupon and current will flow through windings 26, 26', and 26''. The current flowing in winding 26 produces a magnetic effect opposite to the effect produced by winding 27, which will hold the output circuit of this tube closed even though current 50 is no longer flowing through winding 28. Accordingly, current flows through winding 26' in a direction such that a magnetic field is set up to oppose the effect of the field produced by winding 27'. The output circuit of tube 21 with which these windings are associated, will be closed and maintained 55 closed, while the effect of the magnetic field produced by winding 27'' of tube 22 is in a direction such as to aid the magnetic effect produced by winding 26'' thereby opening and maintaining the output circuit in this tube open for the condition described. The 60 output circuit of tube 21 being closed for 65 the condition described, a circuit is completed

including the left-hand winding of polarized relay 31, whereby this relay is operated for causing the reversal of its armature to impress on the line conductor 32 an impulse corresponding to the impulse received on the 70 winding 28 of tube 20.

Likewise, when an impulse of the opposite polarity is received on the tube 28, the output circuit of tube 21 is opened while that of tube 22 is closed, thereby completing a 75 circuit for the other winding of polarized relay 31. The armature of polarized relay 31 for such a condition is thereby caused to reverse its position.

The invention has been disclosed as applied to a particular circuit, but variations from the present showing may be made without departing from the spirit and scope of the invention.

The invention claimed is:

1. In combination, an elongated glass vessel, a cathode and an anode contained in said vessel, an output circuit, a magnetic coil associated with said electrodes for controlling the flow of current between said electrodes, a second magnetic coil for generating a magnetic field for controlling the effectiveness of the field produced by said other magnetic coil, and means operatively associated with said electrodes and said coils for maintaining said output circuit in one of the conditions following the energization of said first magnetic coil, depending on the character of such energization.

2. In combination, a signaling path, an electron discharge device operatively associated with said signaling path, comprising a vessel containing a cathode and an anode, a magnetic coil surrounding said vessel, a local circuit containing said magnetic coil including a source of current to cause said coil to generate a magnetic field sufficient to control the flow of electrons between said electrodes, a second magnetic coil associated with said signaling path for controlling the effectiveness of said other magnetic coil, and a third magnetic coil included in a local circuit and operatively associated with said cathode and anode for producing an effect to oppose said first mentioned magnetic coil.

3. In combination, a signaling path, an electron discharge device operatively associated with said signaling path, said device containing a cathode and an anode, an output circuit, a magnetic coil surrounding said vessel, a local circuit containing said magnetic coil including a source of current to cause said coil to generate a magnetic field sufficient to control the flow of electrons between said electrodes, a second magnetic coil associated with said signaling path for controlling the effectiveness of said other magnetic coil, and a third magnetic coil included in the output circuit for producing

an effect to oppose the effect of said first mentioned magnetic coil only when space current is flowing.

4. In combination, a signaling path, an electron discharge device associated with said signaling path, comprising an evacuated vessel containing a cathode and a cylindrical anode, a plurality of magnetic coils surrounding said vessel, circuit connections for controlling the operation of said coils to control the space current flowing between the cathode and anode, and a pair of magnetically controlled electron discharge devices included in the output circuit of said device, and means controlled by said pair of electron discharge devices for relaying signaling impulses in accordance with the signals received from said signaling path.
5. In combination, a signaling path, elec-

tron discharge device associated with said 20 signaling path comprising an evacuated vessel containing a cathode and a cylindrical anode, a plurality of magnetic coils surrounding said vessel, circuit connections for controlling the operation of said coils to 25 control the space current flowing between the cathode and anode, and a pair of magnetically controlled electron discharge devices included in the output circuit of said first device, and means for maintaining said 30 pair of devices operated in accordance with the previous operation of said first recited device until the electrical condition of said device has been altered.

In witness whereof, I hereunto subscribe 35 my name this 31st day of August A. D., 1922.

LOUIS M. POTTS.
